R. W. STEED,
DISH WASHING MACHINE,
APPLICATION FILED NOV. 22, 1913.

1,180,332.

Patented Apr. 25, 1916.

UNITED STATES PATENT OFFICE.

ROBERT W. STEED, OF NEW YORK, N. Y.

DISH-WASHING MACHINE.

1,180,332.

Specification of Letters Patent. Patented Apr. 25, 1916.

Original application filed January 23, 1912, Serial No. 672,877. Divided and this application filed November 22, 1913. Serial No. 802,516.

To all whom it may concern:

Be it known that I, ROBERT W. STEED, a citizen of the United States, residing at 5 borough of Brooklyn, in the city of New York and State of New York, have invented certain new and useful Improvements in Dish-Washing Machines, of which the following is a specification.

My present invention relates to dish washing machines, the object thereof being to 10 provide a machine particularly adapted for domestic use in homes and small kitchens, although it is equally well calculated to serve for efficient use on a larger scale; and it consists essentially in a centrifugal, 15 turbine or rotary pumping means whereby water is lifted vertically to a point where it can be projected laterally against the dishes and other articles requiring cleansing.

20 In the annexed drawings illustrating my invention, Figure 1 is a perspective view of my improved dish washing machine, a portion of the tank being broken away to expose to view the internal mechanism. Fig. 2 is an enlarged vertical section of the operative mechanical parts of my improved dish washing machine, including more particularly the pumping mechanism. Fig. 3 is a 25 sectional plan view on the line 3, 3 of Fig. 2. Fig. 4 is a sectional plan view on the line 4, 4, of Fig. 2 and indicates especially the appearance of the diffusing vanes and the blades of the water pump. Fig. 5 is an enlarged detail section of a broken away portion of certain of the diffusing vanes and 30 the pump blades, for the purpose of showing their relative location as well as their shape; the section of Fig. 5 being on the line 5, 5, of Fig. 4. Fig. 6 is a sectional view on the line 6, 6 of Fig. 3.

Similar characters of reference designate corresponding parts throughout all the different figures of the drawings.

In carrying my invention into practical effect I provide a main tank 1 of suitable size 45 for containing the dishes and other articles to be washed, as well as the main parts of the operative mechanism, which tank is to be considered as the main washing tank. I 50 utilize an elevated water-heating tank 4, which is supported in any desirable manner, and has the function of heating a proper quantity of water which can be supplied to the washing mechanism. This wa- 55 ter tank 4 has an outlet pipe 10 provided

with a cock 11, which pipe 10 runs downwardly and connects with a pipe 12, see Figs. 1 and 2, which leads to the interior of the tank 1 and connects with other parts of the mechanism there. Under the water tank 4 are gas jets 5 so that in this way the water can easily be heated. The pipe 12 enters a stationary casting 15 provided with a downwardly-projecting outlet nozzle 18 which delivers through a circular opening 19 into the upper revolving circular casting 24. Two vertical pipes 20 and 21 placed diametrically opposite to each other have their upper ends fixed securely into the upper revolving casting 24, and their lower ends fixedly held by a base plate 23. The upper hollow casting 24 is provided with horizontally-projecting outlet pipes 22; any suitable number of them. The pipe 20 is furnished in its lower half with a series of horizontal projecting pipes 25, while the opposite pipe 21 is provided in its upper half with a similar series of horizontal projecting pipes 26. Thus it will be seen that the pipes 25 and the pipes 26 project in opposite 75 directions. While the lower ends of the vertical pipes 20 and 21 are closed and securely held by the horizontal casting 23, the upper ends of said pipes communicate with the interior of the hollow casting 24 and receive a hot water supply therefrom which passes downwardly through said vertical pipes 20 and 21 and finds outlet through the branches 25 and 26 into the tank 1.

Between the pipes 20 and 21 is a water 80 discharge cylinder 16 of uniform diameter throughout, which passes downwardly through the lower casting 23 and is held therein, and which is provided at its upper end with a circular disk or casting 28 securely seated therein and connected thereto, said disk 28 forming part of the bottom of the casting head 24. This circular casting 28 is provided with an upwardly projecting shaft 13 on which is a grooved pulley 14. A 85 belt 29 passes around this pulley and to a small electric or other motor 31. Thus it will be seen that I provide means whereby the shaft 13 is driven, and consequently the cylinder 16 and the casting 24 and pipes 20 and 21 are jointly caused to revolve.

Continuing my description of the discharge cylinder 16, which is really in fact a hollow shaft, I desire to point out that it is provided at intervals with outwardly-pro- 95

jecting pipes 17 similar to the pipes 25 and 26. These pipes are located at any suitable points and are more or less staggered, for example, or so situated that the water ejected 5 through them from the interior of the cylinder 16 may be cast in all directions throughout the interior of the tank 1, see Fig. 1. The branch pipes 17 are provided each with a small perforation, as at 27, to admit air 10 to break the vacuum and thus permit the water to rise higher in pipe 16 and flow out of all the pipes 17, in the whole series to the top of pipe 16. Without the perforations 27 the head of the outflowing water at the ends of 15 pipes 16 can be so great as to prevent the water rising more than a short distance in pipe 16.

The lower end of the cylinder 16 is attached to a conical or bell-shaped casing 35, 20 having also a cylindrical part, the lower end of which is securely fastened to a pump impeller 38, which is clearly shown in section in Fig. 2, and the blades of which, 39, are partially outlined in Fig. 5 so as to indicate 25 their curvature. Inside of the cylindrical portion of the frame 35, just below its conical upper portion, is located a stationary series of diffusing vanes 40, which are shown in section in Fig. 2, and in partial outline in 30 Fig. 5. This circular series of diffusing vanes is carried by a vertical shaft 37 to which the hub of the vanes is fastened by a set screw 41, see Fig. 2, or by some other equivalent device. This shaft 37 is secured 35 to an angle piece or arch 36 in the lower end of a receptacle or well 33, which has a flange 42 at its upper end, said receptacle 33 being located below the central portion 40 of the main tank 1 and supported by means 45 of its flange 42, which rests on the bottom 50 of the interior of said tank. Attached to the lower end of the receptacle 33 is a waste or 55 discharge pipe 32 by which the water is carried away from the machine, said pipe being provided, as shown in Fig. 1, with a hand 60 valve 43 and also a faucet 44. Within the receptacle 33 and concentric therewith, being arranged so as to leave an annular 65 space between it and the cylindrical wall 70 of said receptacle 33, is a cylindrical barrel 75 34 provided with several fingers 45, which project over the flange 42 and rest 80 thereon and serve to support the cylindrical barrel 34 in place. The upper end of 85 cylinder 34 is open as well as the lower end, 90 both ends being free, and cylinder 34 is provided opposite the diffusing vanes 40 with a 95 series of orifices 46 through which the water 100 can pass from the annular space between 105 cylinders 33 and 34. The perforated barrel 110 34 serves to enable the water to be pumped 115 more efficiently when the impeller 38 is rotated; in consequence of the rotation of the 120 casing 35 to which it is attached. The 125 reason for this is, that the rapidly-rotating

casing 35 causes a rapid swirling motion in the water around it, and in the absence of the barrel 34 the water would not flow down through the receptacle 33 to the suction of the pump, but its course would be 70 interfered with by the revolving water around casing 35. It will be evident that, with the diffusing vanes 40 carried by the shaft 37, and thereby held in a stationary position, when impeller 38 with its series of 75 turbine blades rotates, the water in the receptacle 33 will be pumped up and discharged into the cylinder 16, and will be carried upward through said cylinder until it reaches the lateral outlet pipes 17, through 80 which it will be passed and projected in a plurality of streams in different directions throughout the main tank 1, and thus brought into contact with the dishes and other articles that are placed therein to be 85 washed and cleansed.

The dishes to be washed may be supported in any suitable manner within the tank by frames 47, or otherwise, that will hold them in position to receive the water 90 discharged from the nozzles 17, 25 and 26.

The operation of my improved dish washing machine is as follows: After a supply of water has been heated in the water-heating tank 4, the valve 11 will be opened and the water allowed to pass down into the hollow casting 24 and the vertical pipes 20 and 21, emerging thence to fill the receptacle 33 at the bottom of tank 1. As soon as the requisite quantity of water has been supplied from the tank 4 to the tank 1 the valve 11 will be closed. The motor 31 will then be started and this will actuate the pump, and the discharge pipe 16; therefore, as soon as the water fills the pipe 16 it will be thrown out of the branches 17 in a whirling spray which will dash through the different parts of the tank 1 and will impinge briskly upon the dishes which have been placed within the tank, and will then fall back into the receptacle 33 at the base of the tank, and be repumped as often as desired. While the motor 31 continues to revolve, the water will be acted on by the impeller 38 and caused to be driven upwardly through the diffusing vanes 40 and lifted through the hollow cylinder 16 until it reaches the various projecting staggered horizontal outlet pipes 17 through which the water will be projected in a plurality of streams which will strike against the dishes and effectually perform a washing operation thereof. This will be continued until the water in receptacle 33 has been pumped by the centrifugal pumping mechanism and delivered upon the articles to be washed. Of course the water will flow back again and be repumped, usually a number of times, and this operation will be continued until the dishes are properly cleaned. The motor 31 130

will then be stopped and by either using the valve 43 or the faucet 44, the greasy water and other contents of the tank and the receptacle 33 can be withdrawn, after which 5 the valve or faucet will again be closed. Then the motor 31 will be again started and the vertical pipes 20 and 21 set in revolution (as well as the connected parts), and the clean hot rinsing water coming from 10 tank 4 down through pipes 20 and 21 will be thrown out through pipes 25 and 26, and a supply of clean hot water directed against the dishes which will enable them to be rinsed off. It will be found that by these 15 operations the tableware will be effectually cleaned and rinsed and then dried, and everything will take place easily and conveniently with a small number of manual operations and with very little attention on 20 the part of the user.

Many changes in the precise construction and arrangement of the various parts may be made without exceeding the scope of the invention.

25 I do not in this case claim the combination of the tank in which the dishes are supported, a rotatable vertically disposed pipe carrying a series of lateral outlets arranged at different levels, and means for 30 supplying the said pipe with water from outside the tank; nor the said elements when further combined with a rotary pump, of any suitable type, communicating with the tank, a pipe to which the pump delivers and 35 from which the water is discharged against the dishes, and means for revolving the pump and the said vertically disposed pipe; nor the rotary member having two sets of water delivery conduits, one communicating 40 with a water supply external to the tank, and the other receiving water from a pump that is supplied from the tank; as such subjects matter are claimed in my former Letters Patent No. 1,090,420, dated March 17, 45 1914, of which the present application is a division.

What I claim is:—

50 1. A centrifugal pumping means comprising a vertical cylinder with discharge nozzles, an enlarged casing fixed to the lower end of the said cylinder, a second cylinder surrounding said casing to prevent a whirling motion of the water, an impeller at the

lower end of the said casing and fixed thereto, means for revolving the casing and impeller, and a set of stationarily supported diffusion vanes located within the said casing above the impeller. 55

2. The combination of a tank, a well into which the tank is adapted to drain, a revolving cylinder closed at its upper end and provided with a series of discharge nozzles, a casing fixed to the lower end of the said revolving cylinder and located within the said well, an impeller at the lower end of 60 the casing and fixed thereto, and stationarily supported diffusion vanes within the casing above the impeller, together with a stationary shaft on which the impeller is mounted, said shaft constituting a support 65 for the impeller and the casing and likewise supporting the diffusion vanes. 70

3. The combination of a tank, a well into which the tank is adapted to drain, a revolving cylinder closed at its upper end and 75 provided with a series of discharge nozzles, a casing fixed to the lower end of the said revolving cylinder and located within the said well, an impeller at the lower end of the casing and fixed thereto, stationarily 80 supported diffusion vanes within the casing above the impeller, and a cylinder located in the well surrounding the revolving casing and close thereto and freely opening into the well, the said cylinder serving to 85 prevent a whirling motion being imparted to the main body of water in the well. 90

4. A centrifugal pumping and water-distributing device, comprising a cylinder closed at its upper end and provided with 90 water discharge nozzles, a casing fixed to the lower end of the cylinder, an impeller at the lower end of the casing and fixed thereto, a support for the upper end of the cylinder, a stationary shaft on which the 95 impeller is mounted constituting a support for the impeller and casing, such supports permitting the cylinder, casing and impeller to freely rotate, and diffusion vanes supported by the said stationary shaft and 100 arranged within the casing above the impeller.
